UNITED STATES PATENT OFFICE.

JOHN S. MCLEOD, OF BOSTON, MASSACHUSETTS, ASSIGNOR TO THE MCLEOD AIR RAILROAD SIGNAL COMPANY, OF SAME PLACE.

AUTOMATIC RAILROAD-SIGNAL.

SPECIFICATION forming part of Letters Patent No. 275,064, dated April 3, 1883.

Application filed May 21, 1880. (No model.)

To all whom it may concern:

Be it known that I, JOHN STEWARD MCLEOD, at present of Boston, in the county of Suffolk and State of Massachusetts, have invented a new and useful Improvement in Automatic Railroad-Signals, of which the following is a specification.

The object of my invention is to provide a cheap, simple, durable, reliable, and effectual automatic railroad-signal by which the approach of a train is announced far in advance, both by visible and audible signals, by the weight of the forward wheels, which depresses a fulcrum-lever, forcing air from an air-reservoir or bellows through a pipe to the crossing, or to whatever place it may be desired to announce in advance the approach of the train, by setting a train-indicator and releasing a clock mechanism to sound a gong and display a conspicuous sign with the inscription "Inward" or "Outward Train Coming," or "Train Coming! Look Out!" or any other inscription desirable, and may be made to shut and open a gate in advance of an approaching train, and so signal for a given time, or until stopped by the train while passing by, which also winds it up. It also sets another train-indicator or danger-signal at the bellows-house (which is more particularly set forth in another application now in the Patent Office) to block a train following too closely, and thus prevent railroad accidents.

It consists primarily of an incline bar, fulcrum-lever, segment-catch, spring, bellows, and pipe, placed at any desired distance from the place to be signaled, near the side of the railroad-track, in such a way that the car-wheel, in passing over and depressing the incline bar, throws up the longer arm of the fulcrum-lever, which is caught and held by the segment-catch, while the spring between the fulcrum-lever and air-bellows gradually forces the air out of the bellows through the pipe to the points desired to be signaled, where there is an expansion-valve fixed on the other end of the pipe to set the desired signals and alarm, and when the air is forced out of the bellows it relieves the segment-catch, and the fulcrum-lever and incline bar return to their normal position.

It consists, secondly, of a hollow iron post placed on the side of the railroad-track at a highway-crossing or station, having a suitable signal-easing, in which is placed the signal or clock mechanism and expansion-valve. The top part of said casing is made the shape of a drum facing at right angles with the railroad-track, having an opening in the center to be covered by a glass, in which moves the indicating-disk for the use of train and other railroad men. Another part extends over the highway and forms the cross-sign casing, under which is a hollow place for the gong in the lower outside portion of the signal-casing, and which may be protected or covered by a wire screen.

It consists, thirdly, of a movable disk placed in the signal-casing, connected with the expansion air-valve on the end of the pipe which leads from the bellows, in such a way as to be movable to the front of the opening in the signal-casing by the expansion of the valve when an approaching train forces air from the bellows and visibly indicates the approach of the train far in advance, to enable dangerous obstacles to be removed, and thus obviate collisions on the track.

It consists, fourthly, of a clock mechanism mounted in a suitable frame placed in the signal-casing, and having a locking arm or catch connected by a rod with the movable disk and expansion-valve stem, and operated by the gravity of a suspended weight to sound the gong, drop the inscribed sign-board, and display a light when the locking-catch is released by the approaching train, and thus automatically announce its approach far in advance, both by visible and audible signals, obviating the danger of crossing accidents, and thus saving life, property, time, and labor, and adding materially to the safety of railroad-travel.

It consists, fifthly, of a simple arrangement by which trains, in passing by the signal, wind up the clock mechanism and stop the alarm by the wheels passing over an incline bar, arm, or cam connected with the rails, by depressing the shorter arm of a fulcrum-lever and throwing up the longer arm, to which is attached an upright rod whose upper end terminates in a pawl, and to which is attached another rod to

stop the alarm by its upward movement, and also to engage with the winding-ratchet, to which the weight or spring is attached, and winds it up until the said weight or cam on the 5 ratchet engages with a projection on the upright rod, holding up the lever in such a way that the wheels will not contact with the incline bar until the clock mechanism is relieved by the next approaching train, and thus utilizes the weight of the passing trains to wind 10 up the clock mechanism, stop the alarm, and return the signal-board to its normal position, all as will be hereinafter more fully described; and, as will be seen, all the operating mechanism is placed above the grade-level.

Referring to the drawings, Figure 1 is a vertical longitudinal sectional view of the bellows-house and its contents. Fig. 2 is a vertical transverse section of the same. Fig. 3 is a 20 vertical transverse sectional view of the signal-post, casing, and inside mechanism. Fig. 4 is a horizontal view of the same. Fig. 5 is an enlarged vertical transverse sectional view of said post and casing, showing more clearly 25 the important parts. Fig. 6 is a transverse vertical section of signal-post, looking in the direction of the arrow 2. (See Fig. 5.) Fig. 5² is a section through lever P on line y y, looking in the direction of the arrow 1, Fig. 5. Fig. 30 7 is an enlarged view of the clock mechanism. Fig. 8 is a plan view of the same enlarged. Fig. 9 is a section showing more clearly the parts I', i, G', and E'.

Similar reference-letters indicate like parts 35 in all of the figures of the drawings.

Referring to drawings, A represents a house for the bellows and connecting mechanism.

B is an air-chamber or bellows, the upper part of which is made fast to the upright walls 40 of the house A. The bottom part of said bellows is movable, not unlike that of an ordinary blacksmith's bellows.

C is a spring having free ends, one of which is attached to the bottom of the bellows and 45 the other to the long arm of a lever, D. This spring is intended to receive the force of said lever D when it is thrown up by the tread of a passing train of cars. The catch T, secured to the house A, holds the long arm of the lever, 50 and through the elasticity of the said spring the power is gradually imparted to the bellows B to force the air from the bellows through a conducting-pipe, D², running to the signal-post. When the bellows is raised a projection 55 on its lower part comes in contact with an arm, u', and raises said arm up to release the catch T and allow the lever D to drop to a normal position, the bellows thereafter being allowed to refill for action by the next train. For a 60 more particular description of this operating mechanism see my previous patent, No. 250,934.

A' is a signal-post, both faces of which are similar, having a shape suitable to the mechanism to be contained within its walls. In one 65 of the faces of this post is a circular opening, g, through which may be exhibited, from

time to time, disks of arbitrary colors. This opening may be glazed to keep out the weather. At the bottom of this post I provide an opening for the free movement of the lever-arm D'. 70 The base of the post is to be provided with a suitable anchorage to hold it firmly to an upright position in the ground, and the upper portion is provided with a suitable shield for a gong, and an auxiliary casing extending at 75 right angles to the one of its faces adapted to receive and inclose a sign that may be exhibited across a wagon-road crossing.

C² is a movable sign-board, of suitable proportions, upon which may be painted "Train-Coming," "Look Out," or other suitable inscription. This sign is pivoted to the casing A' at a point, i', and counterbalanced by a weight, c³, adapted to slide for adjustment on the arm c'. This sign is dropped to view automatically, and so held while a train is approaching, as will be hereinafter described.

On an arm, z, pivoted in the post on a shaft, a, is formed an annular frame for a disk, B'. Extending from the shaft a is a short arm, d, 90 which connects with the stem g' of an air-valve, T', connected by pipe D² with the bellows B. When air is forced from the bellows-house, as previously described, the diaphragm of the said valve lifts the stem g' to drop the 95 disk B' opposite the circular opening g, where it is exposed to view until the pressure of air from the bellows ceases, when the stem drops by gravity to draw or lift the disk away from exposure.

Pressure of air on the diaphragm may be modified by exhausting it through the cock f.

If desirable, the disk, which is usually of cloth, may have inserted centrally in it a piece of glass, so that at night the rays of light may 105 readily pass through for lighting purposes. If necessary, a similar disk may be arranged for the opposite face of the post, to be operated from the same shaft, a.

To indicate the approach of a train from an opposite direction, a similar bellows to that described, with coacting mechanism, may be placed on the opposite side of the signal, and by spreading the tracks of a double-track railroad a little farther apart at the wagon-road crossing one signal with double mechanism may be used to signal a train on either track. When, however, it can be conspicuously placed on the outside of the tracks, to signal trains both ways, it can be connected with the 115 opposite track by a rod passing through the rails of the first track and terminating with a crank or cam at the side of the opposite track, to support an incline bar to give a certain revolving motion and extend the other end at 120 right angles into the side of the signal-post to connect with another rod, E', to operate similarly to the lever D'. A more particular description of this is unnecessary, as it is simply turning lever D' around at right angles and 125 extending one of its pivots across to the opposite track and forming its end into a crank

to support an incline bar to make one signal do for double tracks.

The disks of different colors which I use answer several purposes—viz., by placing a blue one on the side toward the bellows it will indicate to the engineer as his train approaches that the signals are set, warning all in advance, while by a red one on the other side danger is indicated, so that time is given to clear the track or stop the train in time to prevent a collision, while at the same time the crossing signal-board and gong warn persons on the highway or at the station to look out or prepare to embark.

15 D' is a lever extending from the signal-post to the rail, on the short end of which rests an inclined bar arranged like that at the bellows-house A. (More clearly shown in a previous patent to me, 246,624.)

20 I is an endless chain passing about the periphery of a grooved wheel, K', up between pawls H H, secured upon the ratchet-bar G', and over the toothbed pulley or wheel L', onto which said chain takes hold to revolve said wheel.

25 G' is a winding-ratchet which holds a weight, J, supported upon a spring, K. Said ratchet is supported by the said pawls H H upon the chain I. The pawls H H being pivoted indirectly to the ratchet G' and held to bearing against the said chain by suitable springs, they move freely over said chain when the ratchet is raised, but grip and hold it when the said ratchet is gravitating, causing the 30 chain to move. The movement of the chain causes the wheel L' to revolve. The wheel L' is firmly attached to the same shaft with the wheel L, which engages with a pinion actuating a worm-wheel, M', a worm, M, and a fan, O, above the latter.

35 E' is an upright rod, pivoted at its lower end to the long arm of lever D', and terminating at its upper end in a curved pawl to engage the teeth of the ratchet G', being guided there-40 to by a spring, F, when raised by the said lever D'. The inclined bar d³, pivoted alongside of the railroad-track at the station, operates upon the short arm of the lever D' to lift the rod E' to lift the ratchet and give a higher hold to the pawls H H upon the chain. When the short arm of the lever D' is relieved the long arm drops by gravity and draws down the rod E' with it. Each succeeding car passing over the track repeats the operation of lifting the weight J until its upper end encounters the stop F', attached to the rod E', when further action by the car-wheels is prevented by reason of the lever D' drawing the inclined bar d³ below the plane of the tread of the car-wheels. It is obvious that as soon as the weight descends the rod E' and lever D' will be relieved and be free to act when again influenced by weight of a passing train. A bracket secured to the signal-post has attached 50 to it a guide, i, to direct and steady the movement of the ratchet G'.

65 An offset, I', attached to the guide i, serves

to keep the curved end of the rod E' from coming in contact with the ratchet G' when the lever D' is down, so that when unlocked the 70 weight may be allowed to descend freely and unobstructed while an alarm is being given from the approaching train passing the bellows-house.

Upon the ratchet G', at its lower end, is secured a spiral spring, K, which serves as a seat to the weight J, the function of which is to cushion the shock produced by the quick movement of the long arm of the lever D' acting indirectly upon said ratchet in the operation of winding.

The rod E² is connected with the rod E', and extends upward to engage with and draw the riding-pawl R from off the segment N (see Fig. 5²) to stop the alarm when said rod is raised, 85 with said rod E', by the passing train.

L is the main driving gear-wheel, secured to the same shaft with the chain-wheel L', which engages with a pinion firmly attached on a common shaft with the wheel M'. The wheel 90 M' gears with a screw, M, on the spindle of which is fixed a fly or balance-fan, O. This train of wheels and fan are moved by the action of the gravitating weight upon the endless chain I. The gear-wheel M' is provided 95 with one or more pins, b, extending from one side to engage with a projecting arm, c, of the gong-hammer rod X to draw said hammer and sound the gong Y. The spring c³, secured to the side of the signal-post, serves to return the 100 hammer to position after each stroke of the bell as said wheel M' revolves. One of the pins b also passes through and extends from the side of the wheel M' next to the lever P, to engage with said lever and lift it in the rotation of said wheel, without interfering with the stop K⁶. The pawl R, pivoted to the arm Q, which in turn is pivoted or hinged to the lever P, is lifted with said lever and thrown by a spiral spring, V', over onto a segment, N. 110

Two or more pins may be fixed in the face of the wheel M' next to the gong, so that the gong may be struck rapidly, if desired. The worm M engages the wheel M' and imparts motion to the revolving fly or regulating-fan 115 O. When the pawl R is withdrawn from the segment N the lever P drops to its normal position, and the locking-arm e' engages the fly O to arrest the alarm mechanism. (See Fig. 7.) The lever P is pivoted in the post at P', 120 and terminates at its opposite end in a spring, g⁶. A rod, h, connects this spring end with the sign-board C².

The object in terminating the lever P with a spring end is to avoid interference with the 125 movement of said lever by reason of the action of a strong wind, which might prevent a free movement of the sign-board C². The lever P has also an arm, Q, the extended end of which is adapted to engage with an offset, S, in rear 130 of the segment N, and to hold said segment in position for pawl R, when said pawl is thrown over, to engage the first notch or depression to the right.

The lever P is provided on its upper side with an upright arm, W, to which is pivoted the locking-catch e'. When the signal mechanism is in operation the lever P is held up by 5 the arm Q and pawl R, pivoted thereto, the two latter being thrown over and held to place on the segment N by force of the spring V', as previously mentioned. A cam or collar, T², fixed upon the shaft which carries the wheel 10 M', is provided with a pin, a', adapted to engage with the teeth of the segment N as said cam revolves, influenced indirectly by the gravitating weight—one tooth at a time.

The segment N is provided with an offset, 15 S, (shown in dotted lines,) which, when the pawl R has traversed its limit over the notches of the segment, comes in contact with a projection on the arm Q and throws the said pawl R off from engagement with said segment, allowing the latter to return by a gravitating weight, u, as shown, or, if preferred, by a spring, the ends of which may be attached to the shaft of the segment and the segment itself. When a train is treading upon the bar 25 d³ and lifting up the weight, the rod E², attached to the rod E', serves, by engagement with an offset or loop on the arm Q, to trip the pawl R from engagement with the segment N, and thus stop the alarm mechanism.

30 It is understood of course that with the fall of the lever P the catch e' on the arm W drops with said lever and takes hold of the fly O and holds the same until the said lever is again lifted.

35 The pins b in the wheel M', intended to engage the gong-hammer arm and lever P, can be so placed as not to interfere with said lever and hammer arm when said lever drops into the recess or notch of the cam T², so that 40 the gear-wheels may readily start and be moved by the gravitating weight when the fan is released. The counterpoise u of the segment N is so placed with reference to the toothed portion of the segment that when the 45 pawl R is thrown off the first notch of said segment will return to a point exactly opposite to a point that would be reached by said pawl when lifted to its greatest height.

The length of time that the gong will sound 50 before the offset S will throw the pawl R can be regulated by the number of teeth formed in the segment N. The catch e' is connected with the valve T' by rod f², so that when the car-wheels are treading the incline bar at the 55 bellows-house the hinged catch e' is lifted with valve-stem d and the fly O is released.

The bellows-house, located at a distance 60 from the station, is formed with a hood extending upward from its top to receive a danger-signal attached to a lever-arm pivoted in said bellows-house. Said signal is operated from a diaphragm-valve located on top of the bellows at the same time with the passage of the air through the pipe leading from the bellows to the post at the station or crossing.

65 At a railroad station, where it may be de-

sirable to announce the approach of a train from either direction, a bellows may be located at each side from the said station and connected with a gong and sign-board at said 70 station.

The sign-board of the inward track may be inscribed on its sides, "Inward Train Coming" and "Outward Train Coming." These or other suitable inscriptions may be used to definitely denote the directions of movement of 75 the trains.

The pipes to convey air forced from the bellows may be of any suitable material, though I prefer lead, as such are less liable to corrosion 80 than iron, and may be formed without joints.

The operation of my signaling mechanism may be explained briefly as follows: When a train of cars is passing the bellows-house, which is distant from the station or crossing, the 85 wheels tread upon the inclined bar S' to operate the lever D, the long arm of which is lifted and caught by the catch T and held, while the spring C slowly forces the air from the bellows through the pipe D² to the diaphragm-valve at 90 the station, and simultaneously therewith elevates the danger-signal B" at the bellows-house. The valve T' being influenced by the air pressed from the bellows, the stem d simultaneously influences the disk B' and disengages the 95 hinged catch e' from the fly O. The weight J, being now unlocked, acts upon the chain and drives the train of wheels to lift the lever P, and while said lever is up and the pawl riding and stepping upon the segment N the pins in 100 the wheel M' are tripping the hammer and sounding the gong. While the gong is being sounded the lever P necessarily remains up, and while up the "look-out" sign is exposed to view from the highway. When the train which 105 has set the signal mechanism in operation reaches the station the rod E' in the signal-post is raised and the pawl R thrown off by the rod E², provided the offset S has not thrown off said pawl and the bell has not finished its 110 complement of strokes. When the lever P falls the catch e' engages the fly O and arrests the movement of the weight. While the cars are moving over the incline bar d³ the bar or pawl E' is engaging the ratchet and lifting the 115 weight until said weight comes in contact with the stop F' on the said bar E'. The weight being held by the catch e' indirectly, it in turn holds the inclined bar d³ below the surface of the track for the time being, or until the catch 120 e' is relieved again by another train passing by the bellows-house.

Having thus described my invention, what I claim as new, and desire to secure by Letters Patent, is—

1. An air-bellows operated automatically by the wheels of a passing train, an air-conveying tube, a diaphragm-valve, and a rod, f², in combination with a train of gear-wheels, a lever, P, an endless chain, and a gravitating 130 weight arranged to sound a gong and display signals, as and for the purpose specified.

2. The combination, with an air-bellows operated by spring force, of an air-conveying tube, a diaphragm-valve, and a disk-signal, as and for the purpose set forth.
5. 3. The combination, with the wheels of a passing train of cars, an inclined bar pivoted by the side of a railroad-track, and a lever connected therewith, of an upright bar or pawl connected with said lever, adapted to engage 10 a ratchet and lift a weight, as and for the purpose set forth.
4. The combination, with the clock mechanism described and the lever P, operating therewith, of the bellows, located at a distance 15 from a railroad station or crossing, and the conveying-tube connecting with said station, as and for the purpose set forth.
5. The combination, with bellows B, pipe D², and diaphragm T', of the clock mechanism 20 described, sign C², gong Y, and the mechanism, substantially as described, for operating said signal and gong from said diaphragm, as and for the purpose set forth.
6. The combination, with the lever D', of the weighted ratchet G', spring K, pawls H H, chain I, and wheels K' and L, by which 25 the clock mechanism is wound automatically for starting by the tread of a passing train, as and for the purpose set forth.
- 30 7. The combination, with bellows B and weight J, of the spring K, ratchet G', pawls H H, and chain I, toothed pulley L', wheels L and M', segment N, fan O, pins a' b, lever P, lever-arm Q, pawl R, locking-catch e', diaphragm-valve T', and suitable means for operating the catch e' from the bellows, as and for the purpose set forth.
8. The combination, in a railroad-signal, of the lever P, provided with a spring end, and 40 the movable sign C², connected by a suitable rod, as and for the purpose set forth.
9. In combination with wheel M', provided with pins described, the lever P, hammer X, gong Y, and sign C², as and for the purpose 45 specified.
- 50 10. The combination, with the weighted ratchet G', the wheel M', and pins fixed thereto, of the segment N, pawl R, fan O, lever P, catch e', and rod E², to set in motion, operate, and stop or arrest the herein-described signals, as and for the purpose specified.
11. The combination, with weight J, wheel M', catch e', rod f², valve T', and bellows B, of the sounding-gong Y, movable sign C², and disk B', as and for the purpose set forth.
- 60 12. The bellows B, pipe D², valve T', catch e', wheel M', weighted rack G', gong Y, sign C², and disk B', all constructed and arranged to announce in advance the approach of a train 65 moving on a railroad-track, as and for the purpose set forth.
13. The combination, with valve T', pipe D², bellows B, lever P, and catch e', of the lever D', rod E', weighted rack G', chain I, and the co-operating clock mechanism, substantially as described, whereby an approaching
- train will sound a gong, display a signal or signals, and automatically announce its approach, as and for the purpose set forth.
14. In combination with pipe D² and valve T', the wheel M' and pins attached thereto, pawl R, lever P, segment N, and hammer X, whereby an approaching train will automatically strike repeated strokes on a gong far in advance, as and for the purpose set forth.
15. In an automatic railroad-signal, a segment-wheel, N, having an offset, S, or its equivalent, in combination with the pawl and stop mechanism held out of action by said pawl, as specified.
- 80 16. The segmental toothed wheel N, provided with a concentric gravity-segment, in combination with the lever P and stepping-pawl, as and for the purpose set forth.
17. A riding-pawl, in combination with a pivoted lever, P, a wheel, M', a laterally-impeiling spring, and a weighted rotary segment, whereby said lever is elevated and so held to expose a warning-sign and release a striking mechanism, substantially as and for 90 the purpose set forth.
18. The combination, with a bellows, an air-conveying pipe, the levers described, located adjacent to a railroad-track, and a diaphragm-valve located in a signal-post, of the operating mechanism incased in said post, substantially as described, whereby a locomotive or car moving along on a railroad may automatically set signals, operate and stop or withdraw the same, for the purpose set forth.
- 95 19. The combination, with a railroad-track, a movable inclined bar attached or adjacent thereto, and lever D', of the bar or pawl E', provided with stop F', and the weighted ratchet G', or its spring equivalent, whereby 100 the wheel-gearing and co-operative mechanism may be prepared for signaling and so held intact until freed by a following train at the bellows-house, substantially as specified.
20. The combination, with a gravitating weight or its spring equivalent, an endless chain, a train of gear-wheels, and the co-operating mechanism described, of a treading bar and lever arranged in close proximity to a railroad-track, and a bellows operated by the 105 weight of a passing train to set visible signals and release a sounding-gong, as and for the purpose set forth.
- 110 21. The weight J, suspended from an endless chain by a ratchet-bar and connecting 115 with a clock-gearing, in combination with a spring, K, fixed in a recess of said weight and secured to said bar or ratchet, as and for the purpose specified.
22. The combination of signal C², located at 120 a railroad station or crossing, operated indirectly by means of a jet of air forced from a bellows remotely located, with lever D and spring C, as and for the purpose set forth.
- 125 23. An inscribed signal and gong located at 130 a railroad-station, operated and sounded simultaneously from a distance through the

agency of a bellows, and a spiral spring, C, actuating the same, and by the co-operation of a vertically-moving weight, as and for the purpose set forth.

5 24. The combination, with lever D', rod or pawl E', bar d³, of spring F and weighted ratchet G', as and for the purpose specified.

25. The weighted ratchet G' and the guide i, in combination with bar or pawl E', as and 10 for the purpose set forth.

26. In combination with the weighted ratchet, the bar E' and the projection I', as and for the purpose set forth.

27. The bar or pawl E', in combination with the rod E² and riding-pawl R, substantially as 15 and for the purpose set forth.

In testimony whereof I have signed my name to this specification in the presence of two subscribing witnesses.

J. S. McLEOD.
